US0D1009286S

(12) **United States Design Patent** (10) **Patent No.:** **US D1,009,286 S**
(45) **Date of Patent:** **** Dec. 26, 2023**

(54) **HAND WARMER**

(71) Applicant: **Shenzhen Jialexin Technology Co., Ltd.**, Shenzhen (CN)

(72) Inventor: **Huailun Liu**, Shenzhen (CN)

(73) Assignee: **Shenzhen Jialexin Technology Co., Ltd.**, Shenzhen (CN)

(**) Term: **15 Years**

(21) Appl. No.: **29/811,565**

(22) Filed: **Oct. 15, 2021**

(30) **Foreign Application Priority Data**

Oct. 13, 2021 (EM) 008721989-0001

(51) **LOC (14) Cl.** **24-01**

(52) **U.S. Cl.**

(57) **CLAIM**

The ornamental design for a hand warmer, as shown and described.

DESCRIPTION

FIG. 1 is a perspective view of a hand warmer, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the hand warmer that form no part of the claimed design.

1 Claim, 8 Drawing Sheets
